BELL AND SPIGOT ASPHALT STEEL CORE PIPE

John K. MacKinnon, Mount Pleasant, Tex., assignor to Talco Asphalt & Refining Company, Mount Pleasant, Tex.

Application March 19, 1941, Serial No. 384,178

5 Claims. (Cl. 138—85)

This invention relates to pipes for conveying water, sewerage, or other fluids, and the principal object is to provide such pipe of an improved structure by which the necessary strength is provided by a metallic element which in turn is protected both from the contents of the pipe and from weather conditions exterior of the pipe from corrosion.

A further object of the invention is to provide a composite metal asphaltic pipe with improved means for associating sections by means of which said sections are mechanically interlocked and the asphaltum layers formed into continuous asphaltum sections completely protecting the metallic element from contact with either interior or exterior conditions.

A further object of the invention is to provide improved means for producing pipes of the character indicated.

Various other objects will appear more clearly in connection with the following detailed description.

The invention consists in the novel construction, arrangement, and combination of parts and the methods hereinafter more fully described and claimed.

One sheet of drawings accompanies this specification as part thereof in which like reference characters indicate like parts throughout.

Figure 1 is a side elevation of an improved pipe section partly broken away;

Figure 2 is an enlarged fragmentary cross-section through the associated ends of two pipe sections preliminary to filling the joint with asphaltum;

Figure 3 is a view similar to Figure 2, showing the joint filled with asphaltum;

Figure 4 is a fragmentary vertical cross-section taken on line 4—4 of Figure 3;

Figure 5 is a diagrammatical side elevation illustrating the apparatus and process utilized in the manufacture of the improved pipe; and

Figure 6 is an exploded vertical cross-section through an assembled mold.

In accordance with the present invention a metal tube 1, which may be of relatively thin gauge sufficient to provide the necessary rigidity and strength to the pipe, is associated with a relatively thick inner layer 5 and outer layer 6 of asphaltum.

In the preferred form the pipe sections are formed with a bell at one end and a spigot at the other, adapted to be inserted in the bell end of a similar section.

The bell end of the tubular core member 1 is

5 provided with a plurality of circumferentially spaced detents 4 while the spigot end is provided with a plurality of similarly disposed projections 3, these projections on the respective ends being spaced axially with respect to the respective ends so that they constitute an interlocking joint when the spigot joint of one section is inserted in the bell end of another and rotated slightly therein. The bell end of each section is further provided with an orifice 8 through which the sealing asphaltum may be poured, as hereafter described.

The asphaltum contemplated in connection with this invention would be of a consistency substantially solid but not brittle at normal temperatures and is preferably cast on and in the tubular core member with a thickness equal or substantially greater than that of the core.

10 After the pipe sections are assembled as indicated in Figure 2 molten asphaltum will be poured through the orifice 8 into the channels between the inside of the bell and the outside of the spigot and it will be noted that this sealing layer 7 will contact and coalesce with the abutting ends of the inner asphaltum layers 5, and also with the abutting ends of the exterior asphaltum layers 6 so that in the resulting joint the mechanical interlocking detents 3 and 4 are sealed by the asphaltum 7 against rotation and the inner and outer asphaltum layers 5 and 6 are formed into continuous homogeneous asphaltum conduits completely surrounding the metallic cores of the assembled pipe sections, both interiorly and exteriorly.

15 An efficient mode of manufacturing these improved pipe sections is illustrated in Figures 5 and 6, in the former of which is illustrated a conveyor C upon which are positioned a plurality of hinged molds M and above which conveyor is positioned a container for molten asphaltum T, from which a conduit extends to two valve controlled nozzles 12—12, beneath which the molds M successively pass. Beyond the nozzles 12 a water spray S is positioned by means of which cooling water can be sprayed over the molds to cool the asphaltum.

20 The mold assemblies are illustrated more particularly in Figure 6, in which the mold is shown open and in which is positioned a tubular core 12 upon which is seated a paper tube 10 and upon the upper end of which is positioned a cap 11, having radially disposed wings 15 adapted to position the tubular core 1, which is positioned in the mold with the bell end up. A second paper tube 9 is positioned outside of core 1 and in contact

with the inner sides of the mold proper. With this arrangement it will be noted that asphaltum can be poured between the inner paper tube 10 and core 1 to provide the inner asphaltum layer which will extend only to the bottom edge of the bell part of the section while asphaltum is similarly deposited between metal core 1 and outer paper tube 9 to form the outer asphaltum layer which extends from the upper edge of the bell to the inner edge of the spigot, the paper tube 9 preferably having its bottom edge inturned as at 14 to form a bottom for this lower end.

With the conveyor operating to successively position the molds beneath the nozzle 12 the molten asphaltum can be readily deposited to the requisite depths.

Various modifications in the precise construction, and arrangement of the parts will readily suggest themselves to those skilled in the art, but all within the scope of the present invention as claimed.

It will be understood that the term asphaltum wherever used in this specification, and the appended claims, is intended to include tars and other similar materials.

Having thus fully described my invention, I claim:

1. Composite pipe comprising a metal pipe core having inner and outer pipe sections of substantial thickness, of non-metallic, non-rigid fusible material adhering to the inner and outer surfaces of the metal pipe to form a unitary structure, said pipe and opposite complementary end portions adapted to co-mate with those of a similar section, with means in one of said end portions for admitting fused non-metallic, non-rigid material into fusing relation with the adjacent end portions of similar material of the pipe structure.

2. A plurality of pipes as specified in claim 1 aligned longitudinally with parts of the adjacent metallic sections in interlocking engagement and the inner and outer sections of adjacent pipes bonded with a similar fusible material amal-

gamated with said sections to form a unitary structure.

3. A composite pipe section comprising a metal pipe core formed at one end with a bell having an inwardly directed protuberance and an orifice in its side wall and at its opposite or spigot end having an outwardly directed protuberance, an outer pipe section extending from the outer end of the bell to a point spaced from the opposite or spigot end, an inner pipe section extending from the outer end of the spigot end to the inner end of the bell, said inner and outer sections formed of an asphaltic material and closely adhering to the metal core to form a unitary structure.

4. A plurality of pipe sections as specified in claim 3, arranged in longitudinal alignment with the bell of one section embracing the spigot end of the next and with the protuberances of the adjacent bell and spigot ends in alignment to interlock the sections and the spaces between said adjacent bell and spigot ends filled with asphaltic material amalgamated with the outer and inner pipe sections to form a unitary pipe.

5. A composite pipe section comprising a metal pipe core formed at one end with a bell, an outer pipe section extending from the outer end of the bell to a point spaced from the opposite or spigot end, an inner pipe section extending from the outer end of the spigot portion to the inner end of the bell part, said inner and outer sections formed of a fusible non-metallic, non-rigid material, said bell and spigot portion of the metal core part proportioned so that the spigot portion of one section will be spaced from the bell part of another section when seated therein, with means for mechanically interlocking said parts in such position and means for introducing in fused liquid form similar material to that forming the inner and outer pipe parts into said space between spigot and bell to fill said space and fuse and amalgamate with the adjacent inner and outer pipe parts.

JOHN K. MACKINNON.
